UNITED STATES PATENT OFFICE

2,128,762

GRINDING MACHINE

Walter A. Weed, Orlando, Fla.

Application August 17, 1937, Serial No. 159,608

2 Claims. (Cl. 51—94)

My invention relates to devices for sharpening or grinding tools or the like, having straight or curved edges.

An important object of the invention is to improve the sharpening or grinding device shown in my co-pending application, Serial No. 110,395, filed November 11, 1936, whereby the tool or work being sharpened, when having a curved edge, is given a longitudinally reciprocatory movement, upon being rocked laterally, thereby causing the curved edge to be more uniformly held in engagement with the grinding wheel.

A further object of the invention is to provide a device of the above mentioned character, so constructed that the clamp may be adjusted, when holding work having a straight cutting edge, so that the reciprocatory movement is eliminated, during the rocking movement.

A further object of the invention is to simplify the construction.

Other objects and advantages will be apparent during the course of the following description.

In the accompanying drawing forming a part of this application and in which like numerals are employed to designate like parts throughout the same,

Figure 1 is a side elevation of a device embodying my invention,

Figure 2 is a plan view of the same,

Figure 3 is a longitudinal section taken on line 3—3 of Figure 2,

Figure 4 is a front end elevation of the device, and,

Figure 5 is a transverse section taken on line 5—5 of Figure 1, looking in the direction of the arrows.

In the drawing, wherein for the purpose of illustration is shown a preferred embodiment of my invention, the numeral 10 designates a pedestal or base, upon which is mounted a horizontal shaft 11 pivotally supporting a vertically swinging inverted U-shaped support 12, having sides 13 and 14, the lower ends of which are apertured to receive the shaft 11, as is obvious. Side 14 is preferably longitudinally adjustable and for this reason it is provided with a longitudinally adjustable strap 15, having the aperture at its lower end to receive the shaft 11, and this strap has elongated openings 16 to receive set screws or bolts 17, so that the strap can be clamped to the side 14. The function of having one side of the support 12 longitudinally adjustable is to render it possible to retain the transverse position of the support in true parallel relation with

the axis of rotation of a rotary grinding wheel 18 or the like.

Rigidly secured to the upper end of the support 12 is a guide or block 19, having a pair of generally horizontal parallel openings 20 formed therein, to slidably receive a pair of rods 21 and 22. The rods 21 and 22 are rigidly secured at their forward ends to a block or head 23, having a depending reduced part or shank 24. It is thus seen that head 23 may be adjusted toward or from the support 12, and may be clamped in the adjusted position by a bolt 25, having screw-threaded engagement with the guide 19 and arranged to engage the upper rod 21. A block 26 is apertured to receive the rods 21 and 22 and may be clamped to one or both of these rods and is shown as clamped to the lower rod by a set screw 27 or the like. This block carries an adjustable clamping bolt 28, passing through an elongated slot 29 formed in a reciprocatory latch 30 having another elongated slot 31 near its forward end to receive a guide bolt 32, carried by the head 23. The latch 30 is provided at its forward end with a V-shaped or tapered notch 33, having its central longitudinal axis in alignment with the central longitudinal axis of the latch 30.

The numeral 34 designates a pivot pin or element, having a reduced screw-threaded shank 35 engaging within a screw-threaded opening 36 formed upon the lower end of the shank 24. This reduced screw-threaded portion engages within the opening 36 and may be locked therein against turning movement by a nut 37. Any other suitable means may be employed to rigidly connect the pivot element or pin 34 with the shank 24, 35 so that the pin will be arranged at a right angle to the shank 24.

The numeral 38 designates a work clamp, for holding flat or curved work. This clamp comprises an inner unit provided at one end with a straight jaw 39 and at its opposite end with a circularly curved jaw 40. The inner unit is preferably formed in a unitary casting. The inner unit further comprises a sleeve or tube 41, arranged near the bottom of the curved jaw 40. This sleeve pivotally receives the pin 34 and the sleeve has an enlarged bore 42 for receiving a compressible coil spring 43, engaging a thimble 44, held in place by a nut 45 having screw-threaded engagement with the forward end of the pivot element or pin 34. The function of the spring 43 is to shift the inner unit rearwardly toward the shank 24, the inner unit rocking on the pin 34 and also reciprocating longitudinally 55

5 during its rocking movement. The inner unit is provided upon its rear side with a shifting cam 46 and this cam has a working face 47, vertically inclined from the plane of turning movement of the inner unit, and this working face extends above the sleeve 41 for a considerable distance and terminates near the straight jaw 39. Cam 46 includes a lower face 48, which is also vertically inclined from the plane of turning movement of the inner unit and the inclined face 48 extends to and through the curved jaw 40, but the face 48 is radially much shorter than the face 47. Cam 46 is adapted to engage with an operating part, to be shifted thereby, preferably comprising a 15 steel ball 49, rotatably held within a socket 50, preferably having bearing balls 51. This socket is rigidly secured to a shank 52, in turn rigidly attached to the shank 24. The clamp further comprises an outer unit provided at one end with a straight jaw 53 arranged near and opposite the straight jaw 39 and at its opposite end a curved jaw 54 arranged near and opposite the curved jaw 40. The jaws 53 and 54 are rigidly connected by rods 55 and these rods are slidably mounted within openings 56 formed in the straight jaw 39. The numeral 57 designates a screw-threaded clamping rod provided with a milled head 58. This clamping rod is adapted to engage within a screw-threaded opening 59 formed in the straight jaw 53 or within a screw-threaded opening 60 formed in the curved jaw 54, and to contact with the straight jaw 39 or curved jaw 40. It is thus seen that by manipulating the screw-threaded rod 57, work may be clamped between the straight jaws or the curved jaws of the inner and outer units. The clamping rod 57 is adapted to be received within the notch 33, when the latch 30 is moved forwardly.

10 The operation of the device is as follows:

40 With the clamp adjusted so that the curved jaws 40 and 54 are arranged lowermost, the blade 61 of the work is clamped between these curved jaws. The latch 30 may have been employed to engage the rod 57 to hold the clamp against turning movement during the insertion of the work, and if this has been done, the latch is now moved rearwardly to release the rod 57. The blade 61 being curved work, or work curved in cross-section, the beveled edge 62 of the blade 50 extends rearwardly in opposite directions from its forward end, as shown. With the parts thus adjusted, the beveled edge 62 is held in proper contact with the grinding wheel 18, by the operator holding the support 12 in the left hand and pressing the support toward the grinding wheel. The operator holds the handle of the work or the head 58 of the rod 57 in the right hand and rocks the clamp in opposite directions. As the clamp is rocked to the right, the ball or element 49 riding 55 upon the high portion of the cam face 47 shifts the clamp forwardly toward the grinder, and when the clamp is returned to the neutral or vertical position, the spring 43 shifts the clamp rearwardly, and when the clamp is rocked to the left the ball 49 again riding upon the high part of the cam face 47 shifts the clamp forwardly and the spring 42 again shifts the clamp rearwardly when the clamp is returned to the neutral or vertical position. By this means the clamp 60 and work is moved forwardly when rocked in either direction, which will cause the curved beveled edge 62 of the work to follow the grinding wheel and maintain a substantially uniform pressure against the same, thereby effecting accurate grinding of the beveled surface.

70

75

When it is desired to grind flat work, the clamp is inverted, and the rod 57 removed from the opening 59 and inserted into the opening 60 to engage with the curved jaw 40. When inverted, the short cam face 48 will be out of contact with the ball 49, and there will be no reciprocatory movement of the clamp longitudinally of the pin 34, by virtue of any rocking movement which might occur.

10 However, rocking movement does not ordinarily occur when grinding flat work and the rod 57 may then be held by the latch 30.

15 It may be desirable under certain conditions to dispense with the reciprocatory movement of the clamp upon the rod 34, during the rocking movement, and this can be accomplished by removing the clamp from the pin 34 and again applying the clamp to the pin with the cam 46 on the forward side of the clamp remote from the ball 49. The spring 43 will then be arranged 20 upon the inner end of the pin 34, or might be omitted.

25 It is to be understood that the form of my invention herewith shown and described is to be taken as a preferred example of the same 25 and that various changes in the shape, size, and arrangement of parts, may be resorted to without departing from the spirit of my invention or the scope of the subjoined claims.

30 Having thus described my invention, what I claim is:

1. In a grinding machine, a rotary grinding element, a relatively stationary support arranged upon one side of the grinding element, a supporting element pivotally mounted upon the relatively stationary support to be swung in a plane substantially parallel with the plane of rotation of the rotary grinding element, a pin mounted upon the pivoted supporting element and having its longitudinal axis arranged at substantially a 40 right angle to the axis of rotation of the rotary grinding element, the pin being adapted to be shifted toward and from the periphery of the rotary grinding element, a work clamp comprising an inner unit having an opening pivotally receiving the pin so that the work clamp may be turned upon the longitudinal axis of the pin and also moved longitudinally of the pin, a spring mounted upon the pin to move the inner unit in one direction longitudinally of the pin, said inner 50 unit having a cam which is also mounted upon the pin, an operating element carried by the pivoted supporting element and arranged to engage the cam, an outer unit to coact with the inner unit, and means to draw the outer unit toward 55 the inner unit.

2. In a grinding machine, a rotary grinding element, a relatively stationary support, a movable supporting element mounted upon the relatively stationary support, a shaft mounted upon 60 the movable supporting element and having its longitudinal axis disposed at substantially a right angle to the axis of rotation of the rotary grinding element, a work holder comprising an inner unit having an opening pivotally receiving the shaft so that the inner unit may turn upon the shaft and move longitudinally thereof, said inner unit being provided with a cam which is adjacent to the shaft, said cam including a long portion extending upon one side of the shaft 70 and a short guide portion extending upon the opposite side of the shaft, an operating element mounted upon the movable support and arranged to engage the long portion of the cam to shift the inner unit longitudinally of the shaft when 75

it is turned upon the shaft, the short portion of the cam remaining out of engagement with the operating element when the inner unit is inverted and turned upon the shaft, said short portion serving to guide the operating element back upon the long portion of the cam, means

5 to move the inner unit in an opposite direction to the movement effected by the cam, an outer unit for coaction with the inner unit, and means to draw the outer unit toward the inner unit.
